UNITED STATES PATENT OFFICE.

FRANCIS J. NOLAN, OF OAKLAND, CALIFORNIA.

MACHINE FOR RAISING BARRELS.

Application, filed June 22, 1921. Serial No. 479,582.

To all whom it may concern:

Be it known that I, FRANCIS J. NOLAN, a citizen of the United States of America, and a resident of Oakland, county of Alameda, and State of California, have invented a new and useful Machine for Raising Barrels, of which the following is a specification.

My invention relates to barrel making machinery and one of the objects of the invention is to provide a machine for raising barrels on the bilge. Another object of the invention is to provide a machine in which the staves constituting the barrel are assembled lineally that is, side by side in a row, and then transformed into a circular or cylindrical assembly. Another object of the invention is the provision of a machine in which the staves are mechanically arranged in circular or cylindrical assembly and both ends windlassed or contracted to head size at the same time.

My invention possesses many other objects and features of advantage, some of which, with the foregoing, will be set forth in the following description of my invention. It is to be understood that I do not limit myself to the showing made by the said description, as I may adopt variant forms of my invention within the scope of the claims.

In the drawings, Fig. 1 is a plan view of my machine. Fig. 2 is a side elevation, and Fig. 3 an end elevation of the machine. Fig. 4 is a vertical section, the plane of section being indicated by the line 4—4 of Fig. 3.

In my machine the steps of raising and windlassing are performed and, because of the manner in which the staves are handled, leveling is also accomplished so that separate handling of the barrel for this purpose is avoided. Breakage of the stave during trussing as now practiced in the art is of more or less frequent occurrence and an item of considerable loss. This is partially obviated by steaming the staves in some cases. While steaming may also be practiced with my apparatus, the necessity for it is much lessened since a stave which by the hand process is almost certain to be broken when the barrel is windlassed, will not be injured in my machine.

My machine comprises a conveyor frame including the guide rails 2 and 3 which at one end are mounted by means of brackets 4 upon the shaft 6 journalled in suitable

floor stands 7. The shaft is adjustable longitudinally of the machine by means of set screws 8 and the shaft is driven by a clutch 9 interposed between the shaft and the pulley 11 which is connected by belt 12 to the motor 13. Normally the clutch is engaged by means of the spring 14 but may be disengaged by a foot lever 16 placed convenient to the workman and connected to the clutch by suitable mechanism including the yoke 17, shaft 18, lever arm 19 and link 21. The other end of the conveyor frame is provided with brackets 22 which are mounted on the fixed shaft 23, secured in vertically movable blocks 24 slidably arranged in the pedestals 26. The blocks are controlled as to height by means of the screws 27 which are geared to the transverse shaft 28, rotated to raise or lower the shaft 23 as required by the hand wheel 29. Suitable adjustment of the bearings of the shaft 6 being made at the same time.

The guide rails 2 and 3 are adapted to carry conveyor chains 31 and 32 respectively of the roller type, the upper reaches of the chains rolling along the guide rails. These chains are driven by sprockets 33 fixed on the shaft 6, and at the other end pass over sprockets 34 rotatably mounted on the fixed shaft 23. The outer ends of the guide rails are provided with the vertically extending walls 36, but are open at the top to permit the laying of the staves upon the conveyor chains. The chains are provided at suitable intervals with upwardly extending studs 37 which are so spaced that the exact number of staves required to form the barrel may be laid on the conveyor between two sets of studs. As the conveyor moves past the workman he lays the staves thereon, and if the last stave to be placed is too narrow or too wide as indicated by the studs pressure on the lever 16 disengages the clutch and stops the conveyor until a stave of suitable width is selected and placed to finish out that particular group of staves. At the inner end of the conveyor frame the guide rails are covered with plates 38 so that buckling of the succession of staves is avoided as the conveyor forces the staves out of the guide rails into the forming heads.

Mounted on each pedestal 26 is a head 41 alined in a vertical plane with the ends of the staves. In order to provide for different sized barrels, different sized heads are pro-

vided for my machine, such different sized heads being interchangeable, and the shaft 23 being raised or lowered, as the case may be, to properly align the conveyor with the 5 particular head used. Each head comprises a disk 42 formed with an annular flange 43 thru which a tangential slot 44 is formed for the passage of the ends of the staves. The flange 43 forms the outer wall of an annular way 46, the inner wall of which is formed by a plurality of arcuate heads 47 of radially movable hollow slides 48 which are mounted on the disk 42 by the gibs 49. A coil spring 50 seated at one end in the hub 15 51 and extending into each hollow slide resiliently presses the slide outwardly in a radial direction. A stop 52 on the inner end of the slide limits the outward movement of the slide and its arcuate head, so 20 that the annular way 46 is of a width somewhat less than the thickness of the stave which it receives. In order to have a continuous inner wall for the annular way the adjacent ends of adjacent arcuate heads are 25 notched together or interlocked, giving a continuous periphery but not interfering with the radial movement of the slides.

Movement of the conveyor forces the succession of staves thereon thru the tangential 30 slots 44 into the annular ways. As the last stave of the succession enters the annular ways, the first stave closes in behind it and the studs 37 on the conveyor chain turn downwardly over the sprocket 34 thus leaving the staves in cylindrical assembly in the 35 head, contiguous staves engaging on the bilge line. As the succession of staves is forced around the annular ways, the leading staves are prevented from falling downwardly in the ways by the resilient pressure 40 exerted against them by the arcuate heads of the slides. For a similar purpose, I prefer to provide also a number of flat springs 53 each fixed to a lug 54 set in the flange 43, and engaging resiliently the outside of 45 the staves.

After the lineal assembly of the staves on the conveyor has been converted into the cylindrical assembly in the head, the ends of 50 the staves are pressed inwardly so that the edges of adjacent staves are engaged throughout the entire length of the staves. Such inward movement of the ends of the staves is permitted by the structure of the inner 55 wall of the way 46, that is by the slidably mounted arcuate members 47. Arranged above the longitudinal axis of the conveyor frame is an I-beam 56 upon which is mounted, by means of rollers 57, the carriage 58. Movement of the carriage is effected by 60 means of a ram, the cylinder 59 of which is secured to the carriage and the piston rod 61 of which is secured by bracket 62 to the I-beam. Fluid, preferably air, under pressure, is admitted to the cylinder by means 65

of a valve operated by the lever 63 operated by handle 64 placed convenient to the operator and connected to the valve arm by suitable levers and links. The valve is supplied with fluid thru a flexible hose 66 connected to any suitable source of supply.

Journalled in brackets 67 on the carriage is a shaft 68 to which are rigidly fixed the arms 69 and 70, the latter extending upwardly in the arm 71 and being connected 75 by rod 72 cross head 73, and piston rod 74, to a piston in cylinder 76. Rotatably mounted on the shaft 68 between the arms 69 and 70 is a sleeve 77 upon which are fixed arms 78 and 79 in opposition to arms 70 and 80 69 respectively. An arm 81 also fixed to the sleeve extends upwardly and is connected by rod 82, cross head 83, and piston rod 84 to a piston in cylinder 86. Each of the cylinders 76 and 86 is provided with a suitable valve 87 for controlling the flow of fluid under pressure to either end thereof and the exhaustion of the fluid from the cylinder. The valves are connected by pipes 88 with the hose 66, and are operated 85 by links 89 and 90 pivoted to arms on the rock shaft 91 which is operated by the conveniently located lever 92. Each pair of arms 70-78 and 69-79 constitute a wind-lassing device and are curved as shown in 90 Fig. 2 so that when closed about the ends of the assembled staves, the staves are forced inwardly in like degree and simultaneously at both ends, so that the adjacent edges of adjacent staves are engaged for the full 100 length of the staves.

During the time that the staves are being introduced into the annular ways of the head, the windlassing arms or jaws are 105 opened sufficiently to permit the passage of the staves into the annular ways. Upon the completion of the circular assembly of the staves, the control lever 92 is manipulated to admit fluid under pressure to the cylinders 76 and 86 thus forcibly closing the 110 windlassing jaws upon the staves adjacent their ends. Since the staves are bent inwardly from the bilge, and at each end simultaneously, there is little likelihood of 115 breakage. Furthermore the evenly applied pressure within the rigid curve of the windlassing jaws results in the more even setting of the staves so that much of the labor usually required to perfect the position of the staves in the barrel is avoided. The necessity for leveling is also removed since the heads force the assembling of the staves in the proper position.

After the windlassing arms have performed their function it is necessary to 125 separate the heads so that the carriage may be moved to carry the barrel into a position where the truss hoops may be applied. The heads 41 are secured by cap screws 93 to blocks 94 one of which is slidably mounted 130

on the top of each pedestal 26. The blocks are of arch form and each is provided with a transverse pin 96 adapted to engage in the slot 97 formed in one end of the lever 98 which is pivoted in the pedestal, and on the other end of which is pivotally mounted a nut 99 engaging the threaded end of the shaft 101 which traverses the machine and is controlled by the hand wheel 102. The 10 ends of the shaft 101 are provided with double threads of long pitch so that with a rotation of the hand wheel 102 the heads 41 are moved quickly toward or away from each other. Suitable stops 103 and 104 limit 15 the movement of the blocks 94.

As soon as the heads 41 have been withdrawn, the control lever 64 is manipulated to move the carriage so that the barrel is carried forward to a new position. The 20 trussing hoops are then applied and the control lever 92 manipulated to open the windlassing jaws to release the barrel. The carriage is then moved back into position adjacent the heads and the process repeated.

25 Where the thickness of the staves makes it desirable to steam them before they are windlassed, I arrange a steam box upon the conveyor frame which is, in this case, considerably elongated. Such a device is indicated in dotted lines in Fig. 2, and consists of a suitable housing 106 built around the conveyor and supplied thru pipes 107 with steam from any suitable source.

30 While I have explained the machine of my invention in connection with the manufacture of barrels it is to be understood that my invention applies equally well to kegs, buckets, kits, or other structure formed by the assembling of staves.

40 I claim:

1. A machine for raising barrels comprising a pair of spaced heads formed with alined annular ways, means for introducing a succession of staves into said ways, a carriage, means on said carriage for pressing the ends of the staves inwardly to engage the edges of adjacent staves whereby the assembled staves may be maintained so pressed and shifted beyond the range of the heads, and means for separating the heads.

45 2. A machine for raising barrels comprising a pair of spaced heads formed with alined annular ways, means for introducing a succession of staves into said ways, a carriage, means on said carriage for pressing the ends of the staves inwardly to engage the edges of adjacent staves whereby the assembled staves may be maintained so pressed 50 and shifted beyond the range of the heads,

means for separating the heads, and means for moving said carriage.

3. A machine for raising barrels comprising a pair of spaced vertically disposed heads formed with alined annular ways, 65 means for introducing a succession of staves into said ways adjacent the bottoms thereof, and means for retarding or gradually slowing down the movement of the first stave as the last stave enters the ways.

70 4. A machine for raising barrels comprising a pair of spaced heads formed with alined annular ways, means for introducing a succession of staves into said ways, a carriage, jaws arranged on said carriage 75 for pressing the ends of said staves inwardly to engage the edges of adjacent staves whereby the assembled staves may be maintained so pressed and shifted beyond the range of the heads, and means for operating said jaws.

5. A machine for raising barrels comprising a pair of spaced heads formed with alined annular ways, means for introducing a succession of staves into said ways, a 85 carriage, means on said carriage for pressing the ends of said staves inwardly to engage the edges of adjacent staves and for holding the staves together in such position, means for separating said heads to 90 release therefrom the assembled staves, and means for moving the carriage to position the assembled staves for a subsequent operation thereon.

6. In a machine for raising barrels, a head 95 having a fixed flange forming the outer wall of an annular way for receiving the ends of these staves in cylindrical assembly, arcuate members forming the inner wall of said way and movable inwardly as the ends of 100 the staves are forced inwardly to engage the edges of adjacent staves, and springs for pressing said arcuate members outwardly.

7. In a machine for raising barrels, a head 105 having a fixed flange forming the outer wall of an annular way on the head, arcuate members having interlocking ends slidable on said head in radial lines and forming the inner wall of said way, means for feeding staves into said way, means for pressing the ends of the staves inwardly to engage the edges of adjacent staves, and for conveying the assembled staves so held from the heads, means for retracting the heads 110 to release the staves, and springs for pressing said arcuate members outwardly.

115 In testimony whereof, I have hereunto set my hand.

FRANCIS J. NOLAN.
